Primary Examiner — Sandra S Snapp*(74) Attorney, Agent, or Firm* — Berg Hill Greenleaf
Ruscitt, LLP.(57) **CLAIM**

The ornamental design for a drain channel, as shown and described.

DESCRIPTION

FIG. 1 is a perspective view of the invention;
FIG. 2 is a top plan view of FIG. 1;
FIG. 3 is a bottom plan view of FIG. 1; and,
FIG. 4 is a front side view of FIG. 1, a rear side view being a mirror image thereof.
The broken lines, shown in the drawings, depict portions of the drain channel and form no part of the claimed design.

1 Claim, 3 Drawing Sheets(56)
